JOURNAL BOX AND CONNECTION

Robert B. Cottrell, Chicago, Ill., assignor to
American Steel Foundries, Chicago, Ill., a cor-
poration of New Jersey

Application January 24, 1941, Serial No. 375,736

13 Claims. (Cl. 105—224)

My invention relates to a railway car truck and especially to a form of connection between a journal box commonly associated with the journal end of a wheel and axle assembly and a frame member which normally may be supported thereon.

A general object of my invention is to form a novel friction arrangement in connection with the journal box and the associated frame member, said arrangement being devised in a relatively simple form which may readily be adapted to a usual form of connection between the journal box and the associated frame member.

My invention contemplates a frame member having pedestal jaws between which may be supported in the usual manner a journal box, said journal box forming in the device as illustrated support means for said frame through the medium of a spring group superposed on the journal box.

My invention comprehends an arrangement of such a journal box and supported frame member wherein a plurality of friction shoes may be supported from the journal box for frictional engagement with the pedestal legs of the supported frame member. As devised, my novel arrangement affords friction engagement for inboard and outboard portions of the frame member at opposite sides of the journal box structure.

As illustrated, my novel structure affords resilient resistance to relative lateral motion between the frame member and the journal box and frictional as well as resilient resistance to relative vertical movement between the frame member and the journal box as well as frictional and resilient resistance for a limited distance to relative movement longitudinally of the truck between the journal box and the frame member. The principal formation of the device, however, is to restrict within certain limits of control, by means of the development of friction, relative vertical movements between the box and the supported frame member.

In the device as illustrated,

Figure 1 is a side elevation of a journal box and the fragmentary portion of an associated supported truck frame member.

Figure 2 is a top plan view of the structure shown in Figure 1, and Figure 3 is a sectional view taken in a horizontal plane indicated by the line A—A at either side of the journal box.

Describing my novel structure in detail, the embodiment shown comprises a truck frame member generally designated 2, only a frag-

mentary end portion of which is shown, said frame member being in the form of a well-known type of truss side frame comprising the compression member 4 and the tension member 6 merging adjacent the end of the frame with the integrally formed spaced pedestal jaws 8 and 10 defining the pedestal opening 12 within which may be received in usual manner the journal box 14, and said jaws may be connected at their lower ends by the usual tie bar 11 secured in ordinary manner as at 13, 13. Said journal box 14 is formed with a relatively flat top portion serving as a seat for the spring 16 superposed thereon, said spring being confined between the inboard and outboard arcuate walls 18 and 20 of the frame, said walls being cored away as at 22 and beaded therearound as at 24 to afford a convenient means of inspection for the enclosed spring, the upper end of said spring being afforded a seat against the top wall 26 of said frame member. The inboard end of the journal box is formed with the usual dust guard portion 28, and said box is formed with inboard guide flanges 30, 30 and outboard guide flanges 32, 32 engaging inboard and outboard wear plate surfaces on said frame as indicated respectively at 34 and 36 at opposite sides of said box. The journal box 14 is afforded the usual form of lid 38 hinged at its upper end as at 40 in the usual manner.

On its outboard face, the journal box 14 is formed with wing portions 42 and 44 at opposite sides of the box, each of said wing portions merging with the adjacent pedestal guide flange and being formed as an integral shallow rectangular housing opening inwardly and serving as a convenient receptacle for my novel form of friction device. Likewise, on the inboard face of the box may be formed at opposite sides thereof wing portions 48 and 50 of structure similar to the wing portions at the outboard side of the box and serving a similar purpose.

The view of Figure 3 shows a section through the pedestal jaw 8 of the frame member, said pedestal jaw having in that plane a general U-section with the inboard leg 52, the outboard leg 54, and the main web 56 joining said flanges as shown. Said pedestal leg 8 is provided with a casing or wear plate 58 with inboard and outboard plate portions designated respectively 34 and 36 against which inboard and outboard guide flanges 30 and 32 of the journal box may engage as already described. Within each shallow housing 42, 44, 48, and 50 may be positioned a friction shoe 60, said shoe being a shallow cup of

rectangular form with a flange 62 extending entirely therearound to define the cup structure of the shoe within which may be confined the resilient member or rubber spring 64, said spring likewise having a generally rectangular form somewhat smaller than the shoe within which it is enclosed in order to permit lateral expansion as the rubber pad is compressed. As shown, the rubber pads or springs 64, 64 are under some compression and the degree of this compression may be varied to modify the amount of friction developed at 66, 66 along the engaging friction surfaces at the backs of said shoes and the opposed wear plates which are mounted on the adjacent pedestal.

It will thus be seen that I have provided a novel arrangement of friction means at spaced areas around the journal box, said areas serving as control means to restrict the relative movement which may take place between the supporting journal box and the supported frame member between whose pedestal jaws said box may be confined. It will be readily understood that the degree of friction developed may be modified by varying the character or size of the rubber pads or resilient members housed in each of the friction means as well as by modifying somewhat the character of the frictionally engaging surfaces on the shoes and the side walls of each pedestal.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a journal box and frame connection, a frame member having spaced pedestal jaws defining a pedestal opening, a journal box supported in said opening with inboard and outboard guide flanges engaging said pedestal jaws, a spring group supported on said journal box and affording support for said frame member, said journal box having a plurality of inboard and outboard wing members at opposite sides thereof defining friction housings, friction means confined in each of said housings for engagement with said pedestal jaws, each of said friction means comprising a friction shoe resiliently supported in the associated housing, said shoe being spaced from said housing to permit relative movement therewith in a plurality of directions.

2. In a railway car truck, a frame member having spaced pedestal legs defining a journal opening, each of said legs having a U-section with inboard and outboard walls, a journal box supported in said opening with inboard and outboard guide flanges engaging said pedestal walls, housings formed on said flanges inboard and outboard of said frame and at opposite sides of said box, friction means confined in each of said housings, each of said friction means comprising a friction shoe supported in the adjacent housing and spaced therefrom in a plurality of directions, and a resilient member under compression between the housing and shoe.

3. In a railway car truck, a frame member having spaced pedestals defining a jaw with a friction surface thereon, a journal box supported within said jaw with guide means engaging said friction surface, and means housed in said guide

means resiliently controlling movement of said box in a plurality of directions.

4. In a railway car truck, a frame member comprising spaced pedestal legs of U-section defining a pedestal opening, a journal box supported in said opening with inboard and outboard guide flanges engaging inboard and outboard walls of said legs, a housing integrally formed with each of said guide flanges, friction means confined in each of said housings in engagement with one wall of the adjacent pedestal leg, each of said friction means comprising a friction shoe mounted in the housing and movable therein in a plurality of directions, and a resilient member under compression between said shoe and housing.

5. In a railway car truck, a frame member having spaced pedestal jaws defining a journal opening, inboard and outboard wear plates on said jaws, a journal box in said opening with guide means having slidable engagement with said wear plates, a spring seated atop said box affording support for said frame member, and friction absorbing devices supported from said box at spaced areas thereabout in engagement with said wear plates, each of said friction absorbing devices comprising a friction shoe movably mounted to afford resilient control of said box in a plurality of directions and a resilient member in abutment with said shoe.

6. In a railway car truck, a frame member having spaced pedestals defining a jaw with a friction surface thereon, a journal box supported within said jaw with a housing adjacent said surface, friction means in said housing and spaced therefrom in a plurality of directions, and resilient means under compression between said friction means and said housing, said resilient means controlling movement of said box in a plurality of directions.

7. In a connection between a frame member and a journal box, spaced pedestal jaws on said frame member defining a journal opening, a journal box supported in said opening with inboard and outboard guide means engaging said pedestal jaws, friction means housed in said guide means respectively in engagement with opposite sides of said jaws, each of said friction means comprising a friction shoe movable in a plurality of directions, and a resilient member under compression between said shoe and the adjacent housing.

8. In a railway car truck, a side frame having spaced pedestals, a journal box accommodated therebetween, resilient means mounted on the top of said box and affording support for said frame, inboard and outboard flanges on each side of said box embracing the associated pedestal, a friction shoe mounted on each flange and frictionally engaging the associated pedestal, and resilient means compressed between each shoe and the associated flange, all of said shoes being disposed in horizontal alignment approximately midway between the top and bottom of the box.

9. In a railway car truck, a frame member having spaced pedestals with inboard and outboard friction surfaces, a journal box supported between said pedestals with guide means engaging said friction surfaces, and a friction absorbing device housed in each of said guide means, each of said friction absorbing devices comprising a friction shoe in slidable engagement with the adjacent pedestal and movable with respect to said guide means in a plurality of directions, and a resilient member in abutment with said shoe.

10. In a railway car truck, a frame member

having spaced pedestal jaws defining a journal opening, a journal box positioned in said opening and comprising means gripping each of said jaws, each of said means comprising inboard and outboard flanges on said box, friction shoes movable in a plurality of directions interposed between said flanges and opposite sides of said jaws, and resilient means interposed between said shoes and said flanges and urging said shoes into frictional engagement with said sides.

11. In a railway car truck, a side frame having spaced pedestals, a journal box accommodated therebetween, resilient means mounted on the top of said box and affording support for said frame, inboard and outboard flanges on said box embracing said pedestals, and friction shoes resiliently mounted on said flanges for frictional engagement with inboard and outboard surfaces on each pedestal, said shoes being entirely disposed a substantial distance beneath the top of 20

12. In a railway car truck, a frame member

having spaced pedestals with inboard and outboard friction surfaces, a journal box supported between said pedestals with guide means engaging each of said friction surfaces, and means housed in each of said guide means resiliently controlling movement of said box in a plurality of directions.

13. In a railway car truck, a frame member having spaced pedestal jaws defining a journal opening, inboard and outboard wear plates on said jaws, a journal box in said opening with guide means having slidable engagement with said wear plates, a spring atop said box affording support for said member, and a plurality of friction devices supported from said box in engagement with said wear plates, each of said devices comprising a friction shoe movable in a plurality of directions and a rubber pad urging said shoe into engagement with the adjacent plate and resiliently controlling lateral, vertical, and longitudinal motion of said box.

ROBERT B. COTTRELL.
